UNITED STATES PATENT OFFICE.

FRANK L. O. WADSWORTH, OF SEWICKLEY, PENNSYLVANIA.

WATER-HEATER CONSTRUCTION.

1,108,284.

Specification of Letters Patent. Patented Aug. 25, 1914.

Application filed November 10, 1911. Serial No. 659,546.

To all whom it may concern:

Be it known that I, FRANK L. O. WADSWORTH, a citizen of the United States, residing at Sewickley, in the county of Allegheny and State of Pennsylvania, have invented certain new and useful Improvements in Water-Heater Construction, of which the following is a specification.

My invention relates to automatic control apparatus for hot water heaters, particularly of the so-called instantaneous type, in which fuel is automatically supplied to and cut off from the main burners of the heater concurrently with the turning on and shutting off of the flow of water through the heating coils. Some of the particular objects of my invention are; the control of the fuel supply by the movements of a single valve which is held to its seat at all times save when there is an actual flow of water through the heater coils; the provision of means whereby said valve is moved solely by the action of the thermostatically controlled parts; and the provision of means whereby the thermostatic control mechanism is brought into operative relationship only when water is flowing through the heater.

Other objects of my invention will appear hereafter.

In the drawings which form a part of this specification;

Figures 1 and 2 illustrate in side and front elevation respectively an ordinary form of instantaneous hot water heater provided with one type of my improved automatic control apparatus; Fig. 3 illustrates in cross-section on an enlarged scale the control mechanism of Figs. 1 and 2; Figs. 4, 5 and 6 illustrate modifications of one part of the control mechanism shown in Figs. 1, 2 and 3; and Figs. 7, 8 and 9 illustrate other forms of controls which also embody my invention.

Referring first to the general arrangement of the heater parts as shown in Figs. 1 and 2; A is the casing of the heater; B and C are the upper coils of the heater; D is the lower reverse coil of the heater connected to the upper coils by means of the pipe E; F are the burners mounted upon the usual burner ring; G is the gas supply pipe leading to the casing H of the gas valve; I is the pipe leading from the valve casing to the burner ring, and J is the mechanism for automatically controlling the

position of the gas valve and the flow of gas to the burners. It will be understood that the showing of the heater itself is a conventional one and that the invention resides particularly in the controlling mechanism which is readily applicable to types of heater other than the one illustrated.

Referring now to Fig. 3 in connection with Figs. 1 and 2; 1 indicates the supply pipe leading from the cold water main to the front or lower end of a cylinder 2 which contains the water actuated piston member 3; 4 indicates the passage-way leading to the upper end of the heater coils; and 5 indicates the outlet from the lower reverse coil of the heater. On the lower head of the cylinder 2 I provide an upwardly projecting hollow boss 6, and on the lower side of the piston member 3 I provide a downwardly projecting hollow boss 7 which, when the piston member is in its lowest closed or inoperative position, fits down into the opening in the boss 6, and closes off communication between the inlet passage 1 and the outlet 4 which leads to the top of the heater coils. The inner surface of the boss 6 is provided with a series of tapered grooves 8-8, so that when the piston member 3 is lifted, a passage-way of gradually increasing cross-section is provided for the flow of the liquid from the pipe 1 to the heater inlet 4. The lower end of the boss 7 is perforated for a purpose presently to be described, and secured in it is a stem 9 which passes down through a stuffing box 10 on the lower head of the cylinder, and is secured to a tension member 11. A flexible washer 12 is secured to the lower end of the boss 7 and is held tightly against the opposing face of the cylinder 2—when the piston 3 is in its lowest position—by means of a spring 13, so that in the closed position of the water actuated member, the opening around the stem 9 is sealed and leakage of liquid past that stem is thereby prevented even though the stuffing box 10 may be loose. The water after flowing through the heater coils and emerging from the outlet 5 enters the lower end of a thermostat chamber 14 and passes upward to an outlet pipe 15 which communicates with the house supply system. At the upper end of this thermostat chamber there is a lateral port 16 which enters the upper end of the cylinder 2. The rear or upper end of the boss 7 is bored to receive a cylindrical valve member 17 which

is adjustably secured in position to the upper head 18 of the cylinder 2 by means of a nut 19, and which is provided at its lower end with port slots 20 that afford communication between the upper end of the cylinder 2 and the central opening in the boss 7. A single thermostat member 21 consisting of a hollow tapered tube of copper, brass, zinc or some other material having a high coefficient of expansion, is secured to a boss 22 at the upper end of the thermostat chamber and terminates at its lower end in a perforated head 23 which carries a stud 24 projecting through the cap 25 at the lower end of the thermostat chamber 14. In order to avoid the use of a stuffing box around this stud I provide a rubber tube 26 which is secured at its lower end to an upwardly projecting boss on the cap 25 and at its upper end to the head 23. This tube has sufficient longitudinal flexibility to permit of the necessary expansion and contraction of the thermostat member 21 while hermetically sealing the opening around the stud 24 and preventing leakage of liquid through the stud opening in the cap 25. The stud 24 terminates in a knife edge which is adapted to engage with a thermostat lever 27, this thermostat lever being mounted on two adjustable screws 28—one behind, and the other in front of the sectional plane of Fig. 3—and carries at its outer end a link 29 to which is secured the lower end of a spring 30, the upper end of said spring being in turn connected to a tension member 11. The flow of gas from the fuel supply pipe to the feed pipe which leads to the main burners of the heater via the pipes G and I, is controlled by a gas valve 31 which is normally held seated by a weight 32, and is provided with a stem 33 leading upward through the cap 34 on the gas valve chamber and terminating in a fork 35 carrying an adjustable screw 36 which is adapted to engage with the outer end of the thermostat lever 27. The stem 33 is provided with a flexible washer 37, which, when the gas valve is lifted, is brought into engagement with the under side of the cap 34 and seals the opening around the stem 32 against the escape of gas.

The operation of this mechanism is as follows: When the piston member 3 is in its lower or closed position, the spring 30 is relieved of tension, and the thermostat lever 27 is consequently held by its own weight out of operative engagement with the thermostat parts, so that no movement of those parts—either of expansion or contraction—can affect the position of the gas valve 31. When a flow of water is started through the heater—as by opening some outlet connection with the house supply system—water is withdrawn through the port 16 from the space above the piston member

3, and the greater pressure of the inflowing water on the lower side of that piston will lift it, thus opening a passage-way through the ports 8 to the inlet 4. The tapered form of these ports necessitates a considerable vertical movement of the piston member 3 in order to afford a sufficient port opening for the continuous supply of liquid to the heater coils to take the place of that withdrawn from the pipe 15. The first upward movement of the piston member 3 closes the port openings 20 around the stem 17, and thus compels all of the liquid which flows in through the pipe 1 to pass through the coil inlet 4 and flow through the heating coils. The upward movement of the piston stretches the spring 30 and lifts the thermostat lever 27 into operative engagement with the stud 24 which is secured to the thermostat member 21. The position of this stud is determined by the temperature of the liquid in the thermostat chamber, and if this temperature is below the point at which the mechanism is adjusted to cut off the supply of fuel to the main burners, the spring 30—when placed under tension by the upward movement of the piston member 3—will lift the gas valve 31 from its seat and allow fuel to flow through the gas valve chamber from the inlet pipe to the outlet pipe. But as soon as the temperature of the flowing liquid has reached a predetermined point—which is determined by the adjustment of the screw 36—the expansion of the thermostat element 21 will depress the stud 24 sufficiently to release the gas valve 31 from the tension of the spring 30, and the said gas valve will be closed by the weight 32, thus shutting off the flow of fuel to the main burners of the heater. The immediate reduction in the temperature of the flowing water, and the consequent contraction of the thermostat member 21 will again lift the stud 24 and subject the gas valve once more to the tension of the spring 30, which will again lift it from its seat and reestablish the flow of fuel through the gas valve chamber. These successive actions which result in the closing and opening of the fuel valve 31 will continue with each successive elevation and depression of the temperature of the flowing liquid above and below the point at which the thermostat may be said to act, as long as water continues to flow through the apparatus. When the flow of water is shut off, the piston member 3 will be returned to its lowest position partly by the tension of the spring 30 and partly by the weight of the piston member 3 itself; and the return of said piston member to the closed position finally relieves the spring 30 of all tension, thereby allowing the thermostat lever 27 to drop out of operative relationship with the other parts of the mechanism so that no movements of the thermo-

stat element 21 can, in this closed position of the water actuated member, affect in any way the position of the gas valve 31. If necessary, an auxiliary spring 40 may be interposed between the piston member 3 and the upper head 18 to assist the water actuated member 3 in its return to its lowest position.

In the position shown in Fig. 3, the port 10 opening 20 will be always opened thus affording a free communication between the upper end of the thermostat chamber 14 (and the upper end of the cylinder 2) and the passage leading to the inlet 4, and thus 15 providing for a free circulation of liquid between the inlet and outlet of the heater coils under the heating influence of the pilot light.

Figs. 4, 5 and 6 illustrate merely modifications in the construction of the thermostat member 21. In the construction shown in Figs. 4 and 5 the thermostat member consists of a nest of tubes 41, which are preferably made of iron, steel, Invar metal, 25 or some other material having a comparatively low coefficient of expansion closed at both their upper and lower ends by heads 42 and 43 and filled with liquid such as alcohol, ether, petroleum oil, or other fluid 30 having a high coefficient of expansion, or with paraffin or fusible metal which melts and becomes liquid at a temperature less than that for which the thermostat element may be designed to act. The lower head 43 35 is hollow and is provided with a diaphragm box member 44, the interior of which is in communication with the hollow head 43 and the tubes 41 connected thereto. This diaphragm box member 44 carries at its lower 40 end a stud 24', which, like the stud 24, is adapted to engage with a thermostat lever 27' mounted on pivot screw supports 45 so as to occupy the same relation to the other parts of the mechanism as is illustrated in 45 Fig. 3.

In the construction of Fig. 6, the thermostat element is of the usual composite construction comprising an outer tapered tube 21' of copper, brass, zinc, or some other 50 metal having a high coefficient of expansion, and an inner rod 46 of iron, steel, Invar metal or similar material having a low coefficient of expansion; the two elements 21' and 46 being rigidly secured to a common 55 water tight cap 47 at the closed upper end of the composite thermostat element. The inner element 46 passes down through an opening in the cap 47 to which the lower end of the tube 21' is secured, and terminates 60 in a loop 48 which loosely embraces the end of the thermostat lever 27' and is adapted to engage therewith through the medium of two adjustable screws 49, one of which—as shown—is located behind the 65 cross-sectional plane of Fig. 4, and the other

of which is in front of that plane; the thermostat lever 27' being in this case pivoted on a single central screw 50 symmetrically located between the planes of engagement of the two screws 49. The other parts of 70 the mechanism are of the same construction and are arranged in the same way as shown in Fig. 3, the reversal of the thermostat supports being necessary because of the fact that the heating of the tube 21' permits the 75 arm 27' to move upward instead of downward as is the case in the arm 27 of Fig. 3 when the tube 21 is heated. The general mode of operation of the mechanism illustrated in each of the Figs. 3, 4, 5 and 6 is 80 substantially the same.

Fig. 7 illustrates a construction resembling in many respects the construction of Fig. 3, but differing therefrom in certain details relating principally to the form of 85 the water actuated element. In this figure 1', indicates the cold water supply pipe, which in this case communicates directly with the inlet 4' to the heater coils. A port 51 leads from the cold water inlet to the upper end 90 of the cylinder 2' which contains the water actuated piston member 3'. The water after passing through the heater coils emerges from the outlet 5' and enters the lower end of a pipe 52 which leads upwardly 95 to the thermostat chamber 14'. A port 53 leads from this chamber to the space below the piston member 3', which in this case is actuated solely by differential pressures as will be presently explained. The piston 100 member 3' is provided with a stem 9' which passes upwardly through the top wall of the cylinder 2' and terminates in a head 54 on which rests a weight 55. The weight 55 is provided with a fork 56 which carries an 105 adjustable screw 57, said screw being adapted to engage a lever 59 that is pivoted on screws 60 and projects at its other end into the thermostat chamber 14'. This left hand projecting portion of this lever 59 passes 110 loosely through a fork 61 which is secured to the upper end of a stem 62, said stem passing down through a stuffing box 63 in the lower wall of the thermostat chamber 14' and being connected at its lower end to an 115 adjustable right and left hand sleeve 64. The other end of this sleeve 64 is connected to the stem 33' of the gas valve 31' which gas valve controls the flow of gas through the pipes G' and I' to the burners. Flexible 120 washers 37' and 12' are secured respectively to the gas valve 31' and fork 61 and serve to seal the opening around the stem 33' when the gas valve is in its opened position, and the opening around the stem 62 when said valve 125 is in its closed position. The thermostat member which I illustrate in this figure, consists of a flat disk shaped chamber 65 mounted on a cap 66 which closes the upper end of the thermostat chamber 14'. The interior 130

opening of the disk shaped chamber 65 is filled with some liquid having a high coefficient of expansion, and preferably having a considerable viscosity such as petroleum oil or mercury, or with a material like paraffin or fusible metal which is solid at low temperatures but melts at a temperature less than that for which the thermostat is designed to act. The lower head of the chamber 65 is provided with a central sleeve or tube 67 in which is accurately fitted a plunger 68, which may be provided with any suitable packing means (not shown); and the end of this plunger terminates in a knife edge which is adapted to engage with the extreme left hand end of the lever 59. A tightly fitted and packed screw 69 affords means for filling the thermostat 65, and also for varying the interior volume of said thermostat chamber. The upper end of the water actuated piston stem 9' is shouldered to engage with a poppet valve head 70 which, when the piston member 3' is in its raised or closed position, is lifted to uncover the port opening 71 and thus affords free communication between the liquid on the upper side of the piston member and the liquid in the upper thermostat chamber 14'. The spring 72 interposed between the head 70 and the head 54 serves to keep this valve seated and close off the opening to the port 71 when the piston member 3' is lowered. A pipe 15' leads from the upper part of the thermostat chamber 14' to the house supply system.

The operation of the mechanism shown in Fig. 7 is as follows: When there is no liquid in the apparatus, or when it is filled with liquid at rest, the piston member 3' is held in its elevated position by means of a spring 73, the tension of which is sufficient to lift the weight 55 and hold the screw 57 out of engagement with the end of the lever 59. In this position of the parts, the stem 62 which leads to the gas valve 31' is relieved of all tension, and no action of the thermostat can affect in any way the movement of said gas valve, which is held to its seat by its own weight. But as soon as a flow of water is started through the heater, the two sides of the piston member 3' will be subjected to a differential pressure produced by the resistance of the flow of the liquid through the heater coils and the parts are so proportioned that under this difference of pressure the piston member 3' will be depressed, compressing the spring 73—and later the spring 72—thus allowing the weight 55 to act upon the lever 59. If the temperature of the liquid in the thermostat chamber 14' is less than that for which the thermostat is designed to act—as determined by the adjustment of either the sleeve 64 or the screw 69—the left hand end of the lever 59 will be raised by the weight 55 thus opening the gas

valve 31' and allowing fuel to flow from the supply pipe to the feed pipe, which communicates with the main burners of the heater. This valve will remain open until the temperature in the thermostat chamber 14' reaches such a point that the expansion of the liquid in the thermostat box 65 forces the plunger 68 into contact with the left hand end of the lever 59 and thereby lifts the weight 55 and relieves the stem 62 from the pull of this weight. The gas valve 31' will then close under its own weight—supplemented, if desired, by the action of another weight or spring—thereby shutting off the supply of fuel to the main burners of the heater. The continued flow of water through the apparatus will reduce the temperature in the thermostat chamber 14'—with the corresponding contraction of the liquid in the thermostat box 65—and this will result in a retraction of the plunger 68, thus permitting the weight 55 to once more act on the stem 62 and open the gas valve 31'. These alternate opening and closing movements of the gas valve under the joint control of the weight 55 and thermostat will continue with the successive depression and elevation of the temperature of the flowing liquid below and above the point of thermostatic control as long as liquid continues to flow through the heater. But as soon as the flow of liquid is stopped, the pressures on the two sides of the water actuated member 3' are equalized, and this member is then lifted by the action of the spring 73, and the lever 59 is relieved from the controlling influence of the weight 55, thereby freeing the stem 62 from all control and preventing any further movement of the gas valve until the parts have once more been brought into operative relationship by again establishing a flow of liquid through the apparatus.

As in the previous case, the return of the water actuated member 3' to its closed or inoperative position opens the port communications between the water on the inlet side of the piston and the water on the outlet side of the heater and permits of a free circulation of the liquid through the heater coils under the influence of the pilot light.

Fig. 8 illustrated another embodiment of my invention in which the construction and arrangement of parts is somewhat different than in the preceding figures. In this apparatus 1² indicates the pipe through which cold water is supplied to the heater, 3² indicates the water actuated member, which in this case is in the form of a poppet valve normally held to its seat by a spring 75, and 76 indicates a connection leading from the space above the said water valve to the cold water inlet (not shown) at the top of the heater coil. After passing through the heater, the water emerges as before from an

outlet 5²; enters a thermostat chamber 14² and passes therefrom to a pipe 15² which communicates with the house supply system. The thermostat chamber 14² contains a liquid thermostat member comprising two concentric, corrugated tubes 77 and 78 closed at both ends by heads 79 and 80, and having the space between these tubes and said heads filled with liquid having a high coefficient of expansion such as alcohol or ether or petroleum oil. A stem 81 is secured to the upper head 79, passes down through an opening in the head 80 and is threaded at the lower end to receive an adjustable nut 82 that bears upon and supports a knife edge 82. This knife edge is adapted to make engagement with the forked end of the thermostat lever 84 which is supported on pivot screws 85; and to the long arm of said lever 20 is secured a stem 86 having at its lower end a head 87 adapted to engage with a threaded collar 88 on the end of the gas valve stem 32². The gas valve 31² is of the same general construction as that shown in Fig. 3 and 25 controls the flow of gas through the pipes G² and I² to the burners. The water actuated poppet valve 3² is provided with a stem 9² which passes upward through a stuffing box 10² in the cap of the water valve chamber and bears at its upper end against a leaf spring 90, the outer end of which is normally out of engagement but can be brought into contact with the long arm of the thermostat lever 84 by the upward movement of 30 the water actuated member 3².

The operation of this mechanism is substantially the same as that of the mechanism already described and will be readily understood with a very brief description. 40 When there is no liquid in the apparatus, or when it is filled with liquid at rest, the parts of the mechanism occupy the position shown in the figure in which the gas valve 31² is free from all controlling or restraining connection with the thermostat mechanism, and in which therefore, the said gas valve is held to its seat—no matter what may be the position of the thermostat parts—by its own weight, supplemented if 45 desired, by the effect of an added weight 32² or a suitable spring. But as soon as a flow of water is started through the heater, the water actuated member 3² is raised away from its seat, against the restraining influence of the spring 75, and the spring member 90 is thereby brought into operative engagement with the lever 84. If the liquid in the thermostat chamber is below the temperature at which the thermostat is 50 designed to act—as determined by the adjustment of either the thumb nut 82 or the threaded collar 88—the long arm of the lever 84 will be lifted by the spring member 90 and the gas valve 31² raised 55 away from its seat, thus permitting fuel to

flow from the inlet pipe to the outlet pipe, which communicates with the main burners of the heater. This flow of fuel will continue until the temperature of the water in the thermostat chamber 14² rises to such 70 a point that the expansion of the thermostat lifts the stem 81 sufficiently to free the gas valve connections from the lifting influence of the spring member 90, thereby allowing the gas valve 31² to close and shut off the 75 flow of fuel to the pipe. When the flow of liquid through the heater is stopped the water valve 3² will be returned to its seat by the spring 75, and the spring member 90 thereby withdrawn from engagement with 80 the thermostat lever 84, thus freeing the gas valve parts from all restraining control by the thermostatic mechanism until the time when a flow of water is once more established through the heater coils. In this 85 form of control apparatus no provision is made in the apparatus itself for opening the circuit between the inlet and outlet of the heater when the water actuated member is in its closed position. Such circulation 90 may be provided for, if desired, by a by-pass check valve connection between the outlet pipe 15² and the upper end of the pipe 76 which leads to the cold water inlet 4 (see Figs. 1 and 2); of the heating receptacle. Such a by-pass check valve as is here referred to, is shown, for example, in the patent to Shook No. 993,723.

Fig. 9 illustrates a very compact and self contained form of control mechanism embodying the improvements forming the subject matter of this application. In this form of water actuated member, the thermostatic control member and the gas valve are all contained in a single casing 93 which 100 is provided with a port connection 51² communicating with a cold water supply pipe 1³, a hot water inlet 94 communicating with the heater hot water outlet 5³ and a hot water outlet 95 communicating with the pipe 15² 105 which leads to the house supply system. Another pipe 76³ leads from the cold water inlet 1³ to the top coil inlet 4, not shown in this figure. In this construction the water actuated member is a corrugated box or 110 diaphragm 96 which is secured at one end to the head 97 containing the ports 51² leading to the cold water inlet 1³, and is closed at the other end by a recessed head 98 containing a spring member 99, which, when 115 the member 96 is in its normal position of rest is substantially free from tension. At the left hand end this spring member 99 engages with a perforated collar 100 which slides freely within the bore of the recessed 120 head 98 and is held out of engagement with the left hand end of said head—when the water actuated member is in the position of rest—by a stud 101 secured to the cap 97 of the water chamber 93. The right hand 125

end of the spring member 99 bears against a collar 102 carrying a stud 103, which is adapted to engage with the upper recessed end of a lever 104. This lever 104 is pivoted on supporting screws 105 in the sides of the box 93 and its lower end terminates opposite a short stud or stem 62³ which passes through a stuffing box 63³ and engages with an adjustable head 64³ on the outer end of the gas valve stem 33³. The said gas valve stem passes through a suitable stuffing box in the front wall of the gas valve chamber containing the gas valve 31³ which is normally held to its seat by a spring 106 and controls the flow of gas through the pipes G³ and I³ to the burners. The lower portion of the water chamber or casing 93 is separated in part from the upper portion by a partition wall 107, and in this lower portion, just opposite the hot water inlet port 94 is located the thermostat element 14³, which in this case consists of a single corrugated tube closed at both ends and filled as before with some liquid having a high coefficient of expansion, or with some material like paraffin or fusible metal which is ordinarily solid, but which becomes liquid at a temperature less than that at which the thermostatic control mechanism is designed to act. The front head of the thermostat member 14³ is provided with a stud 108 which is supported in position in a recess in the lever 107.

The operation of this mechanism is as follows: When no liquid is flowing through the apparatus, the water actuated member 96 is maintained in the position shown in the figure by its own elasticity, and as in this position the spring member 99 is free from tension the gas valve member 31³ will always be held closed by the tension of the spring 106. But as soon as a flow of water is started through the heater, the pressure of the liquid in the chamber 93 is reduced by the withdrawal of water through the house service pipe 15³ and by the resistance to the flow of the water through the heater coils. The pressure on the inside of the corrugated diaphragm member 96—which communicates through the ports 51³ with the inflowing water—is then greater than the pressure on the outside of said diaphragm member and the latter is correspondingly expanded moving the head 98 to the right. The first initial movement of this head releases the collar 100 from the stud 101 and closes the port openings 110 around the end of this collar thereby preventing any further direct movement of the liquid from one side of the diaphragm member to the other. The movement of the head 98 to the right also places the spring member 99 under compression tension, thus forcing the stud 103 into operative engagement with the lever 104. If at this time the flowing liquid is cold, the ther-

mostat member 14³ will be contracted and the stud 108 will be withdrawn from engagement with the lever 104, thus leaving the latter free to move under the action of the now compressed spring member 99, and such movement of the lever 104 will force the stem 63³ into engagement with the head 64³ of the gas valve stem 33³ thereby raising the gas valve 31³ from its seat against the lesser tension of the spring 106, and allowing fuel to flow from the supply pipe to the feed pipe and thence on to the main burners of the heater. This flow of fuel will continue until the temperature of the flowing liquid has sufficiently expanded the thermostat member 14³ to bring the stud 108 into engagement with the lever 104 and move the lower end of the latter far enough to the right to free the gas valve from the controlling influence of the spring member 99. The gas valve will then be closed by the action of the spring 106, and will remain closed until the thermostat 14³ has again contracted sufficiently to allow the gas valve parts to be brought once more under the controlling influence of the spring member 99. The successive opening and closing movements of the valve 31³ under the control of the spring member 99 is determined by the contraction and expansion of the thermostat member 14³ and will continue as the temperature of the flowing liquid falls and rises alternately below and above the temperature at which the thermostat may be set to act, this point of thermostatic control being varied by the adjustment of the screw nut 64³. When the flow of water is shut off the pressure on the inside and outside of the diaphragm box 96 is equalized, and said box will contract to its original position shown in Fig. 9 by virtue of its own elasticity, thereby relieving the spring 99 of any compression tension and correspondingly freeing the lever 104 from any controlling influence of either the spring member or of the thermostat parts. When the member 96 has returned to its normal unexpanded condition, the ports 110 will be opened by the contact of the stud 101 with the perforated collar 100 and a free communication will be established between the inlet and outlet of the heater coils, thus permitting water to circulate therein under the influence of the still burning pilot light.

It will be obvious to those skilled in the art that various detail changes and modifications in construction may be made in any of the above described forms of mechanism without departing from my invention. Thus, for example, in the form illustrated in Fig. 7, I may use in place of the thermostat member there shown, a thermostat member similar to that in Fig. 6; said substituted thermostat member being simply inverted in position and placed directly in the pipe 52. Similarly in the construction shown in Fig. 120

8, I may separate the support for the gas valve box from the support for the rest of the apparatus, placing the former near the bottom of the heater shell as in the forms shown in Figs. 3 and 7. Various other changes and substitutions of the various elements one for another will also readily suggest themselves in various adaptations of the mechanism to different constructions.

10 Having thus described my invention and illustrated its use, what I claim as new and desire to secure by Letters Patent is the following:—

1. In combination in an instantaneous water heater, a water actuated member operated by opening and closing the outlet from the heater, a gas valve yieldingly maintained in closed position when not acted upon externally, a thermostat controlled by the water of the heater, a controlling lever for the gas valve intermediate the water actuated member and the gas valve, a resilient connection between the controlling member and water actuated member whereby the controlling lever is moved by the water actuated member to open the gas valve when the outlet from the heater is opened, and an operative connection between the thermostat and controlling lever, whereby such lever is held against movement by the water actuated member tending to open the gas valve when the temperature of the water is above a predetermined point, and whereby such lever is permitted to be moved by the water actuated member to a position to open the gas valve when the temperature of the water is below such predetermined point.

2. In combination in an instantaneous water heater, a water actuated member operated by opening and closing the outlet from the heater, a gas valve yieldingly maintained in closed position when not acted upon externally, a thermostat controlled by the water of the heater, a controlling lever for the gas valve intermediate the water actuated member and the gas valve, a resilient connection between the controlling member and water actuated member whereby the controlling lever is moved by the water actuated member to open the gas valve when the outlet from the heater is opened, and an operative connection between the thermostat and controlling lever whereby such lever is moved to a position to secure the closure of the gas valve against the force of the said resilient connection when the outlet from the heater is open and the temperature of the water in the heater rises above a predetermined point for which the thermostat is set and whereby the said lever is permitted to be moved by the water actuated member to a position to open the gas valve when the temperature of the water is below such predetermined point.

3. In combination in an instantaneous water heater, a water actuated member operated by opening and closing the outlet from the heater, a gas valve yieldingly maintained in closed position when not acted upon externally, a thermostat controlled by the water in the heater, a controlling member for the gas valve, a resilient connection between the controlling member and water actuated member whereby the controlling member is moved in one direction by the water actuated member to open the gas valve when the outlet from the heater is opened, and a direct connection between the controlling member and thermostat for moving the said controlling member in the other direction to secure the closure of the gas valve against the force of the said resilient connection when the temperature of the water in the heater rises above a predetermined point.

4. In combination in an instantaneous water heater, a water actuated member operated by opening and closing the outlet from the heater, a gas valve yieldingly maintained in closed position when not acted upon externally, an expansible member acted upon by the water of the heater, a controlling member for the gas valve, a resilient connection between the controlling member and the water actuated member whereby the controlling member is moved in one direction by the water actuated member to open the gas valve when the outlet from the heater is opened, and means carried by the expansible member for directly and positively moving the controlling member in the other direction to secure the closure of the gas valve against the force of the said resilient connection when the temperature of the water in the heater rises above a predetermined point.

5. In combination in an instantaneous water heater, a water actuated member operated by opening and closing the outlet from the heater, a gas valve yieldingly maintained in closed position when not actuated upon externally, a controlling member for the gas valve, a resilient connection between the controlling member and the water actuated member whereby the controlling member is moved in one direction by the water actuated member to open the gas valve when the outlet from the heater is opened, and an expansible member acted upon by the water of the heater and carrying means engaging the controlling member for positively moving such controlling member reversely and in the direction of the expansion of the expansible member to secure the closure of the gas valve against the force of the said resilient connection when the temperature of the water in the heater rises above a predetermined point.

6. In combination in an instantaneous

water heater, a water actuated member operated by opening and closing the outlet from the heater, a gas valve yieldingly maintained in closed position when not acted upon externally, a thermostat controlled by the water of the heater, a controlling member for the gas valve, a yielding tension connection between the controlling member and water actuated member whereby the controlling member is moved in one direction by the water actuated member to pull open the gas valve when the outlet from the heater is opened, and a direct connection between the controlling member and thermostat for moving the said controlling member in the other direction to secure the closure of the gas valve against the force of the said resilient connection when the temperature of the water in the heater rises above a predetermined point.

7. In combination in an instantaneous water heater, a water actuated member operated by opening and closing the outlet from the heater, a gas valve yieldingly maintained in closed position when not acted upon externally, a thermostat controlled by the water in the heater, a controlling lever, a connection therefrom to the gas valve, a resilient connection between the lever and the water actuated member whereby a movement of the controlling lever is secured by the movement of the water actuated member to open the gas valve when the outlet from the heater is opened, and a positive connection between the lever and thermostat whereby the lever is moved to a position to secure the closure of the gas valve against the force of the said resilient connection when the temperature of the water in the heater rises above a predetermined point.

8. In combination in an instantaneous water heater, a water actuated member operated by opening and closing the outlet from the heater, a gas valve yieldingly maintained in closed position when not acted upon externally, a thermostat controlled by the water in the heater, a controlling member for the gas valve, a stress applying means therefor, a connection between the controlling member and water actuated member so arranged that a movement of the water actuated member secures the application of the stress applying means to the controlling member and an opening of the gas valve, but at the same time permits a movement of the controlling member in the reverse direction without moving the water actuated member, a direct connection between the controlling member and thermostat for moving the said controlling member to secure the closure of the gas valve when the temperature of the water in the heater rises above a predetermined point.

9. In combination in an instantaneous

water heater, a water actuated member operated by opening and closing the outlet from the heater, a gas valve yieldingly maintained in closed position when not acted upon externally, a thermostat controlled by the water of the heater, a connection between the gas valve and thermostat having lost motion when the water of the heater is below a predetermined point and the outlet from the heater is closed, and means controlled by the movement of the water valve for taking up the lost motion between the thermostat and gas valve and placing such connection under stress tending to open the gas valve when the outlet from the heater is opened, the said thermostat being arranged so that it acts positively to overcome the said stress when the temperature of the water heater rises above a predetermined point.

10. In combination in an instantaneous water heater, a water actuated member operated by opening and closing the outlet from the heater, a gas valve yieldingly maintained in closed position when not acted upon externally, a thermostat controlled by the water of the heater, a connection between the gas valve and thermostat having lost motion when the water of the heater is below a predetermined point and the outlet from the heater is closed, and means controlled by the movement of the water valve for taking up the lost motion between the thermostat and gas valve and placing such connection under a yielding force tending to open the gas valve when the outlet from the heater is opened.

11. In combination in an instantaneous water heater, a water actuated member operated by opening and closing the outlet from the heater, a gas valve yieldingly maintained in closed position when not acted upon externally, a thermostat controlled by the water of the heater, a connecting means between the gas valve and thermostat having lost motion when the water valve is in inoperative position, and means controlled by the water actuated member and arranged to apply a yielding force to take up the lost motion in the said connecting means and to operate the said connecting means to open the gas valve when the outlet of the heater is opened and the temperature of the water in the heater is below the said predetermined point.

12. In combination in an instantaneous water heater, a water actuated member operated by opening and closing the outlet from the heater, a gas valve yieldingly maintained in closed position when not acted upon externally, a thermostat controlled by the water of the heater, a connecting member between the gas valve and thermostat which is normally out of operative contact with both the gas valve and thermo-

stat, and a strain member controlled by the water actuated member in such manner as to bring the gas valve and the thermostat into operative connection with the connecting member and subject the latter to actuating stress when water is flowing through the heater, and to free the said gas valve and thermostat and the connecting member from operative relationship when the water is at 10 rest.

13. In combination in an instantaneous water heater, a water actuated member operated by opening and closing the outlet from the heater, a gas valve yieldingly 15 maintained in closed position when not acted upon externally, a thermostat controlled by the water of the heater, a connecting member between the gas valve and thermostat which is normally out of operative contact with both the gas valve and thermostat, and a variable strain member 20 interposed between the water actuated member and the said connecting member and adapted to bring the thermostat and gas 25 valve into operative relationship with each

other when water is flowing, and release such parts from actuating stress when the water is at rest.

14. In combination in an instantaneous water heater, a water actuated member operated by opening and closing the outlet from the heater, a gas valve yieldingly 30 maintained in closed position when not acted upon externally, a thermostat controlled by the water of the heater, a connecting member between the thermostat and gas valve which is normally free from any operative stress when the water is at rest, and a strain member interposed between the water actuated member and connecting 35 member and adapted to place the latter under operative stress only when the water is flowing through the heater.

In testimony whereof I have hereunto signed my name in the presence of the two 40 subscribed witnesses.

FRANK L. O. WADSWORTH.
